(57) **CLAIM**

The ornamental design for a silicone sleeve for a tinned can, as shown and described.

DESCRIPTION

FIG. 1 is an isometric view of a silicone sleeve for a tinned can of an embodiment according to the present invention; FIG. 2 is a right side view of the silicone sleeve for a tinned can of FIG. 1;

FIG. 3 is a left side view of the silicone sleeve for a tinned can of FIG. 1;

FIG. 4 is a top view of the silicone sleeve for a tinned can of FIG. 1;

FIG. 5 is a bottom view of the silicone sleeve for a tinned can of FIG. 1;

FIG. 6 is a front view of the silicone sleeve for a tinned can of FIG. 1; and,

FIG. 7 is the rear view of silicone sleeve for a tinned can of FIG. 1.

The broken lines depict portions of the silicone sleeve for a tinned can that form no part of the claimed design, and environment that forms no part of the claimed design.

1 Claim, 6 Drawing Sheets
